(57) **CLAIM**

The ornamental design for an icon for a portion of a display screen, as shown and described.

DESCRIPTION

The FIGURE is a front view of an icon for a portion of a display screen showing our new design.

The broken line showing of a portion of a display screen is for the purpose of illustrating environmental structure and forms no part of the claimed design.

The icon shows a lock associated with an open page having representative lines across it indicative of information contained on the page.

1 Claim, 1 Drawing Sheet
